United States Patent Office

Des. 223,756
Patented June 6, 1972

223,756

ARM CHAIR

Saul G. Steinhart, 21 Austin Road,
Hamden, Conn. 06512

Filed Sept. 3, 1970, Ser. No. 24,824

Term of patent 14 years

Int. Cl. D6—02

U.S. Cl. D15—1

Fig. 1

Fig. 2

Fig. 3

Fig. 4

Fig. 5

FIG. 1 is a front elevational view of an arm chair, embodying my new design.

FIG. 2 is a rear elevational view thereof.

FIG. 3 is a right side elevational view thereof, the left side elevational view being a mirror image of FIG. 3.

FIG. 4 is a top plan view thereof, and

FIG. 5 is a front perspective view thereof.

I claim:

The ornamental design for an arm chair, as shown and described.
